UNITED STATES PATENT OFFICE.

EMIL HOFFMANN, OF COLOGNE, GERMANY.

DEVICE FOR TENSIONING AND BINDING BANDS ON BOXES, BALES, AND THE LIKE.

Application filed July 13, 1925, Serial No. 43,359, and in Germany July 15, 1924.

This invention relates to devices for tensioning bands of hoop iron and the like around boxes or bales and then binding together the ends of the tensioned band.

- 5 Devices of this general character are known for binding wires on boxes and in such devices gripping jaws are carried by levers and moved by means of a screw cam for the purpose of applying the tension. 10 The cams are mounted loosely on their shaft and are returned to their initial position by a spring after each operation of tensioning the wires is completed. For the purpose of applying the tension the levers carrying the 15 gripping jaws are moved apart in opposite directions by the rotation of the cams.

This known form of tensioning device is not suited for stretching and binding flat bands, as the grippers, when applying the 20 tension, move in the arc of a circle and it is thus impossible to guide the ends into a clip sleeve, which is used in the known manner for binding the ends of the hoop iron. The return of the tensioning cams by 25 means of springs is also objectionable as the grippers are thereby held up by the cam and failure of the machine to operate properly may result from the improper return of the grippers. Finally the known device 30 mentioned is not adapted for use with boxes or bales requiring widely different degrees of tension and the range of usefulness of any given machine was therefore strictly limited.

- 35 According to this invention these defects are removed. In the first place the gripper jaws, according to this invention, are carried by slides movable in a straight line parallel to the axis of the rotatable shaft or spindle 40 on which the screw cams are rigidly mounted. In this way the ends of the bands during tensioning are properly entered in the binding sleeve and are in exact register, so that reliable binding of the band can be 45 effected. The screw cams terminate in a peak at their highest point, which is the point located nearest to the gripper slides, and from this peak the cam suddenly recesses. The cam rollers carried by the gripper slides thus rise on the screw part of the cam to apply the tension, until the rollers reach the peak, whereupon the gripper slides 50 are quickly returned to their initial position under the action of suitable spring means, conveniently located inside the hollow shaft or spindle. A return movement of the cams

is thus rendered unnecessary. The hand lever which effects the rotation of the spindle and that which effects the operation of the punch of the binding device are so located 60 that they act mutually as steadyng handles, and thereby render the entire machine more convenient and serviceable. The return movement of the gripper slides under the action of their springs may be adjusted by 65 means of stop pins and the degree of tension applied on rotation of the tensioning cams thereby altered as required.

Referring to the accompanying drawings:

Figure 1 is a front elevation of a band 70 tensioning machine made in accordance with this invention.

Figure 2 is a plan of the same.

Figure 3 is a front elevation showing the position of the gripper slides after the 75 bands have been tensioned and the binding sleeve is in position to be operated on by the punching device so as to clamp or bind the ends of the bands together.

Figure 4 is a cross section at right angles 80 to Fig. 3.

In carrying the invention into effect, a hollow shaft or spindle *c* is supported rotatably in bearings *b* formed in upstanding brackets cast on the bed *a* or fixed thereto in any suitable manner. On the shaft *c*, there are rigidly fixed two cams *d*, which, on the side facing the centre of the machine, have spiral or screw formed working faces. At the point nearest to the centre of the machine on these cam faces, the screw face terminates in a peak, *d*¹ after which, in the direction of rotation of the shaft *c*, there is a drop in the cam in the form of a substantially axial portion *d*². The gripper slides *f* are suitably guided to slide along the shaft *c* parallel to the axis of the shaft and in a straight line. These slides carry arms *f*¹, which support the rollers *f*², which ride on the screw shaped face of the tensioning 90 cams *d*. Wedge shaped gripping jaws *g*, operated by a hand lever *h*, are provided to grip the fastening band *B* in the known manner. There are two such slides and two 95 cams, so arranged that on rotation of the shaft *c*, the slides are first caused to approach to the centre of the machine, that is to move from the position shown in Figure 2 to that shown in Figure 3. In doing so, the 100 band *B*, which has its ends clamped in the gripper jaws *g* is tensioned.

The rotation of the shaft *c* is effected by

means of a ratchet lever k having a pawl l pivoted to it and engaging in a ratchet wheel i keyed to the hollow shaft c . The tensioned band B has its ends entered in a flattened sleeve H which has been inserted in the punching device o and is of such form that it embraces the ends of the band B and allows these ends freely to pass through it during the operation of tensioning. It is known to use such sleeves for binding together the ends of hoop iron bands, the binding operation being effected by indenting or suitably punching the sleeve so that it effectively holds and retains the band B in the tensioned state. The stamping device o is located about the centre of the machine and comprises a slidable punch n centrally mounted in a suitable upstanding bracket on the machine bed a and two side clamps m also slidable in the said bracket o^3 and adapted to clamp the sleeve H during the tensioning operation and also during the punching of the sleeve by the punch n . For this purpose, a pivoted lever o^4 , suitably mounted on the bracket o^3 has on its boss three cam parts, two similar side parts o^1 , which operate the clamps m , and a central cam part o^2 , which operates the central punch n . As can be seen in Figure 4, the lever o^4 is turned counter clockwise to the left to clamp the sleeve, and in this position acts as a steady to hold the bed a during the operation of tensioning and the hand lever k in a similar way performs the same function during the operation of punching.

Inside the hollow shaft c there is provided a spiral spring p which is fixed at its ends to cross bars s , which pass radially through side slots r in the shaft c and have small rollers s^1 at their ends which contact with the gripper slides f so as to press these slides apart and thereby cause the rollers f^2 to follow the contour of the screw shaped faces of the cams d . When the shaft c is rotated so that the top half is coming towards the observer in Figure 1, the spring p is compressed until the peak of the cams is reached. In this position the punching operation is performed on the sleeve H . Immediately the peak of the cams has been passed, the slides are free to be moved back into their initial positions by the direct action of the springs p , without requiring the cam to be given a rotation in the reverse direction.

The distance which the gripper slides spring back under the action of the spring mechanism described, may be regulated in any suitable manner, so as to vary as required the degree of tension imparted to the band B . In the form shown, this regulation is effected by means of stops, which may be in the form of pins adapted to be inserted in one or other of the holes t in

the bed plate a . In this way only a portion of the screw cam face is effective and the travel of the gripper slides correspondingly reduced.

I claim:

1. A device for tensioning and binding bands of hoop iron or the like around boxes, bales or the like, having in combination a bed plate, a rotatable shaft mounted on said bed plate, tensioning cams mounted rigidly on said shaft to rotate therewith at all times, gripper slides mounted to slide on said shaft and adapted to be moved axially by said tensioning cams, resilient means adapted to maintain said gripper slides in operative contact with said tensioning cams, and means located on said bed plate between said gripper slides for binding the tensioned band.

2. A device for tensioning and binding bands of hoop iron or the like around boxes, bales or the like having in combination, a bed plate, a rotatable shaft mounted on said bed plate, gripper slides for gripping the ends of and tensioning a band, said slides being movable in straight lines parallel to the axis of the shaft, screw shaped tensioning cams mounted to rotate with said shaft and adapted to operate said slides, said cams having each a peak, which becomes operative when the slides have tensioned the band, and a sudden drop portion which immediately follows the peak, spring means operable on said gripper slides to cause the same to follow the contour of the screw cam and means for binding the ends of the tensioned band.

3. A device for tensioning and binding bands of hoop iron or the like around boxes, bales or the like having in combination a bed plate, a rotatable shaft mounted on said bed plate, said shaft being hollow and having radial slots extending axially therein, gripper slides for gripping the ends of and tensioning a band, said slides being guided on said shaft, tensioning cams mounted to rotate with said shaft and adapted to operate said slides in the direction to tension the band, a spiral spring within the said hollow shaft, cross pins on the ends of said spring and projecting radially through the slots on the shaft to press the gripper slides into engagement with the cam faces and operate the said slides in the reverse direction to that required for tensioning the band and means located on the bed plate between the gripper slides for binding the ends of the tensioned band.

4. A device for tensioning and binding bands of hoop iron or the like around boxes, bales or the like having in combination, a bed plate, a rotatable shaft mounted on said bed plate, gripper slides for gripping the ends of and tensioning a band, said slides being guided on said shaft to slide axially

on said shaft, tensioning cams mounted rigidly on said shaft to rotate therewith and adapted to move said gripper slides towards one another to tension the band, a ratchet lever for operating said shaft, means located on said bed plate between the grippers for binding the ends of the tensioned band and a hand lever for operating said means, said recited hand levers being arranged to act mutually as steadyng levers during the operation of one or other of said levers.

5. A device for tensioning and binding bands of hoop iron or the like around boxes,

bales or the like having in combination, a 15 bed plate, a rotatable shaft mounted on said bed plate, gripper slides for gripping the ends of and tensioning a band, said slides being movable in straight lines parallel to the axis of the shaft, tensioning cams mounted rigidly on said shaft to rotate therewith and adapted to move said gripper slides towards one another to tension the band, means for adjusting the sliding movement of said slides and means located on the bed 20 plate between said gripper slides for binding the ends of the tensioned band.

EMIL HOFFMANN.
